METHOD AND APPARATUS FOR STAGE
KNEADING

Raymond H. Jebens, Wellsville, Ohio, assignor to
The Patterson Foundry & Machine Co., East
Liverpool, Ohio, a corporation of Ohio

Application October 14, 1950, Serial No. 190,095

12 Claims. (Cl. 259—104)

1

This invention relates to the kneading of various materials such as plastics, pastes, liquids, granular or crumbly materials, and the like in a continuous operation, and provides an improved method and apparatus for this purpose. Kneading includes such operations as dispersing, blending, masticating, smearing, mixing etc. The invention provides an integrated continuous method of kneading the material in several adjoining zones in which the material is smeared in a succession of back and forth movements in each zone, the material remaining in each zone and continuing to undergo such kneading therein unless other material be added to the operation to effect its movement from one zone to an adjoining zone, and moving the material progressively from zone to zone by adding material at one zone and removing it at another zone.

The invention provides an improved combination of apparatus comprising at least two oppositely rotatable intermeshing blades, each blade having a plurality of helically disposed leading edges and escape openings and each blade being mounted to rotate in a cylindrically shaped trough, and means for continuously introducing material into the trough and removing kneaded material from the trough.

An important feature of the invention is the provision of two similar, preferably identical, blades arranged in reversed end-for-end relation, each blade including several blade units comprising two end units and one or more intermediate units, each unit having at least two leading edges equidistant from the rotary axis and substantially diametrically opposite each other, the edges being helically shaped and arranged so that the corresponding edges of adjacent units converge towards each other. The end of each unit has a cut-out portion embracing one of the edges and the units are so arranged in the blades that the cut-out portions adjoin and form escape openings in the blades at the edges between the units for the flow therethrough of the material undergoing kneading. The edges on each side of the blades embrace a sort of undulating wave with corresponding points on the edges of the two blades in the same radial plane. The edges of the units in each blade are more than one-half, preferably about two-thirds, the length of the unit and therefore overlap the corresponding edges of the other unit. The blades may be unitary or assembled by mounting several units on a single shaft.

2

In an advantageous and preferred embodiment, the unit profiles forwardly of each edge with respect to the direction of rotation are constructed as an involute curve to intensify progressively the pressure of the material between the blades and on the troughs as the blades rotate. The involute profile preferably follows the curve of the edge in its helical direction.

10 The two troughs are preferably of identical cylindrical shape and are connected together longitudinally to form a ridge or saddle extending the length of the blades. The blades are so mounted in the troughs that the edges and profiles clear the inner cylindrical surfaces and each other at any selected distance, and the edges and profiles of the blades are so shaped that they force the material against the troughs and each other effecting a pressing, rolling and smearing of the material while also moving some of the material axially in the troughs to the escape openings where a part of the material escapes from the edges of one blade and is then positioned to be engaged by the edges of the opposite blade.

15 20 25 The blades form a series of kneading stages and zones, each zone comprising two stages and four blade units with an escape opening in each blade of each stage. In the kneading stages the material is retained while kneading and only displaced by added fresh feed material. When the feed of material is stopped, the material in the trough undergoing kneading remains in its particular stage and may mix indefinitely in each stage until displaced by new material or released.

30 35 40 45 The kneading blades of the invention are so constructed and arranged in the troughs and with respect to their profiles, edges and escape openings that the added material will be conveyed axially in different directions at the same time in each of the several stages. During operation, one edge of one unit moves some of the material axially in one direction towards an escape opening while one edge of the adjacent unit moves some of the material axially in the opposite direction towards another escape opening where it can be picked up by an edge of a unit of the other blade, thus avoiding the circumferential movement of the entire mass of the material under treatment. The blades permit some of the material to escape from the adjacent edges of one blade into the path of movement of the adjacent edges of the other blade, reversing the axial and circumferential movement of the material. By suitably regulating the

rate of addition of material, the retention time in the kneading operation is determined.

These and other novel features of the invention will be better understood after considering the following discussion taken in conjunction with the accompanying drawings, in which:

Fig. 1 is an elevational view of kneading apparatus of the invention with parts removed;

Fig. 2 is a plan view of the apparatus of Fig. 1 with parts removed;

Fig. 3 is a view at the discharge end of Fig. 1;

Fig. 4 is an enlarged side view of one pair of adjacent blade units of the invention;

Fig. 5 is a sectional view at 5-5 of Fig. 2;

Figs. 6 to 12 are sectional views at lines 6-6 to 12-12 respectively of Fig. 4;

Fig. 13 is a perspective of the units illustrated in Fig. 4;

Fig. 14 is a plan view of another form of kneading apparatus which may be used in practicing my invention, and

Figs. 15, 16 and 17 are sectional views at 15-15, 16-16 and 17-17 of Fig. 14 respectively.

The kneading apparatus illustrated in Figs. 1 to 13 comprises a horizontally disposed trough member 1 formed of two partly cylindrical troughs 2 and 3 joined together along their longitudinally contacting edges to form a centrally disposed saddle 4. The trough is formed of any suitable metal, with or without a heating or cooling means, and is securely mounted in any suitable manner as on the legs L. The kneading blades 5 and 6 are of identical construction and are mounted in reversed end-for-end relation on shafts 7 and 8 which are concentrically mounted in the troughs 2 and 3 respectively. At the discharge end, the blades are mounted in bearings 10 and 11 and at the feed end they are mounted in bearings 12 and 13. Blade 6 is driven by the pulley 14 on the shaft 8, while blade 5 is driven in the reverse direction by the intermeshing gears 16 and 17 on shafts 7 and 8 respectively.

The trough cover 20 has inlet openings 21 and 22 for the addition of the materials to be kneaded and the trough 23 is for the discharge of the kneaded material from the trough member 1. Any suitable means may be provided for spraying liquids or adding gases to the material in the trough, and other openings for the discharge of material may be provided in the bottom or sides of the cylindrical troughs.

A kneading apparatus employing the individual kneading units U of the blades is described and claimed in the copending application of Eardley Harry Ford, Serial No. 5,301, filed January 30, 1948, now Patent 2,559,418, granted July 3, 1951. These units are preferably hollow and have hub portions 24, 25 at their ends for engaging the shafts 7 and 8. The shafts 7 and 8 make tight contact with the hubs 24 and 25 of the blade units. The shafts may be hollow, as in Figs. 4 and 13, and holes may be provided in the shafts for the passage from the central opening of the shaft of a heating or cooling fluid into the hollow portion of the units to heat or cool the units, as the case may be. By reason of the relatively large surface of the units, they provide a very effective heat transfer medium.

Each blade unit of shaft 7 has two leading edges 30 and 31 helically and concentrically disposed with respect to the axis of its shaft and two arcuate cuts 32 and 33. The adjoining units being in reversed end-for-end relation, the mating arcuate cuts 32 and 33 form escape openings E. The end 34 of edge 30 is approximately

45° to 90° more or less in advance of point 35 with respect to the direction of rotation. The blade portions forwardly of the leading edges have profiles 36 and 37 of pronounced curvatures, preferably as involute curves. The profile curves 36 and 37 follow the curves of their respective helical edges.

The blade units of shaft 8 are identical with the units of shaft 7, having similar leading edges 30' and 31', arcuate cuts 32' and 33', edge ends 34' and 35', involute curves 36' and 37', and escape openings E' (Fig. 1).

It will be noted that leading edges 30 and 30' are diametrically opposite edges 31 and 31', respectively, but are longitudinally displaced, as shown in Figs. 1 and 4. The edges of the blades generate a cylinder on rotation and the edges are over one-half, preferably about two-thirds, the length of the blade so that the end portions at the escape openings overlap. The adjacent units on the shaft are so positioned that if the leading edges were continuous they would form a sort of undulating wave or sine-like curve. The units of both shafts are in alternate reversed end-for-end relation. Each pair of units as in Fig. 4 in combination with its opposing pair of units diametrically opposite and contained within the overall length as Fig. 4 forms a zone Z which in turn comprises two stages of mixing.

It will be noted with reference to Figs. 1, 2, 4, and 13 that leading edges adjacent the escape openings converge in the sense that they move the material towards the escape opening while the continuous leading edges of the other blade at right angles thereto diverge in the sense that they cause the material to move divergently from the center point of the edges.

The shafts of the two blades are so positioned with respect to each other and to the troughs that the edges and involute surfaces on rotation clear each other and the trough but a small fraction of an inch for dispersing or kneading most materials. However, the clearance may be adjusted as desired.

In carrying out a method of the invention with the apparatus of Figs. 1 to 13, the kneading of the material in any one zone will be described since similar kneading will be carried out simultaneously in the other zones. As the two kneading blades rotate in the direction of the arrows, the material contacted by the leading edges 30, 31, 30' and 31' and the involute surfaces 36, 37, 36' and 37' is squeezed and smeared with progressively increasing pressure against the troughs 2 and 3 to the point of minimum clearance at the edges 30, 31, 30' and 31'. It is also squeezed and smeared with progressively increasing pressure between the involute surfaces 36, 37, and 36', 37'. By reason of the helical shape of the surfaces and edges and their relation to each other, the material is wiped and smeared in repeated back and forth movements and some of the material is moved axially from both units of each zone toward the escape openings E and E'. The escape openings E in edges 30 of blade 5, for example, are in a transverse plane to the crests of the abutting edges 31' of the corresponding units of the same stage of blade 6 (Fig. 2). The material forced into the escape openings E is thus positioned to be engaged by the converging or abutting edges 31' of blade 6 from which it is moved from the center in opposite axial directions. The material similarly forced through the escape openings E' is positioned to be engaged by the edges 31 of blade 5. The material is accord-

ingly moved convergently by one blade towards and through an escape opening and then divergently by the leading edges of the opposite blade in a succession of similar operations.

The material undergoing pronounced mastication, blending, dispersion and kneading in each zone will remain indefinitely in the zone without moving axially to any appreciable extent to an adjoining zone unless more material be added. The rate of travel of material from the inlet end at ports 21 and 22 to the discharge trough 23 is determined within practical limits by the rate of addition of fresh material. The invention accordingly provides a means of effecting any desired amount of kneading merely by controlling the feed.

Figs. 14 to 17 illustrate apparatus which may be used in carrying out the method of my invention. The apparatus comprises a horizontally disposed trough member 40 formed of two partly cylindrical troughs 41 and 42 joined together along their longitudinal contacting edge to form a centrally disposed saddle or ridge 43. The trough is formed of any suitable metal and may be provided with heating or cooling means. The mixing or kneading blades 44 and 45 are of identical construction and are mounted in reversed end-for-end relation in the end bearing members 46 and 47. The blades are driven in synchronism in the direction of the arrows by any well known means. The material to be kneaded may be added at the right end, as viewed in Fig. 14, or at any intermediate place, and is removed through the opening 48.

The mixing or kneading blades may also be formed of five blade units U' connected together at the junctions J by welding or otherwise to form the continuous kneading blades. The blades may be formed as unitary members and can have any suitable number of units. Ducts D for a heating or cooling fluid are provided in the blades. The adjoining units are connected together in reversed end-for-end relation and the corresponding blade units of one dispersion blade overlap those of the other, as best shown in Fig. 14. The apparatus of Fig. 14 comprises two zones Z and a half-zone Z'. Each zone includes four blade units so arranged that the two units of one blade form a stage and converge towards the junction while the two units of the other blade form another stage and diverge at the junction.

The blade units U' have cross-sectional areas, as shown in Figs. 15, 16 and 17, with leading edges 50 and 51 which on rotation clear the troughs 41 and 42 by but a fraction of an inch. The blade units are in intermeshing relation but do not come into close contact. The leading edges of the units are helically disposed but do not continue in the same direction throughout the blades. The direction of the leading edges and blades reverses at each junction, and the corresponding parts of the units of one blade are displaced longitudinally with respect to the units of the opposite blade whereby there is an appreciable overlapping as seen by comparing point 52 of blade 44 with point 53 of blade 45.

In carrying out an operation of the invention in the apparatus of Figs. 14 to 17, the material to be kneaded is fed from above into the trough member at the right end with reference to Fig. 14 and if it is continuously added it will be moved along the trough from zone to zone and be discharged at 48. The blade units of one blade knead the material against the trough while causing it to move longitudinally in one direc-

tion. Each unit of both blades having the same helical direction moves the material in the same direction. Each unit of the blade which is helically disposed in the opposite direction also forces the material against the trough but moves the material in the opposite longitudinal direction. With reference to any zone, the units of blade 45 move the material convergently toward the junction J in opposite directions while the units of blade 44 move the material in both directions divergently from juncture J' in opposite directions. In each zone there are two stages of mixing, the material of each stage tending to remain separate until material is fed into one stage, when part of the material in that stage is forced into the other stage. At the junction J' material from either side approaches this junction and is thrown back to remain in that stage which corresponds to one blade unit length. The material which is converged by one blade is positioned to be met by the opposite blade which moves it divergently. As a consequence the material undergoes a series of back and forth movements in the troughs and will continue to be kneaded in each zone more or less indefinitely unless it be displaced by added material.

I claim:

1. The method of kneading material in an integrated continuous operation which comprises kneading the material in several adjoining zones each of which comprise two stages in which the material is kneaded in a succession of back and forth movements in each zone, the material remaining in each stage of each zone and continuing to undergo such kneading therein unless other material be added to the operation to effect its movement from one stage to an adjoining stage, and from one zone to another zone, and moving the material progressively from stage to stage and zone to zone by adding fresh feed material at one stage and removing it at another stage during the kneading operation.

2. In the method of claim 1, adding material to the material being kneaded at an intermediate stage.

3. The method of kneading material in an integrated continuous operation which comprises kneading the material in several adjoining zones and stages including an inlet zone, at least one intermediate zone and an outlet zone in each of which zones the material is moved axially convergently and divergently with back and forth movements, the material undergoing kneading remaining in each stage of each zone indefinitely unless displaced by added material, and displacing the material from each stage of each zone by adding fresh feed material at the inlet zone and removing kneaded material at the outlet stage during the kneading operation.

4. The method of kneading material in an integrated continuous operation which comprises kneading the material simultaneously in several adjoining zones including an inlet zone, at least one intermediate zone and an outlet zone, each zone comprising two kneading stages, in each zone kneading the material while moving it convergently and divergently, part of the material moving in one direction in one stage while another part of the material is moving in the opposite direction in the stage, whereby the material will remain indefinitely in each stage unless additional material be added, and moving the material undergoing kneading from the inlet zone through the intermediate zone to the outlet zone

solely by adding fresh feed material at the inlet zone during the kneading operation.

5. Apparatus for the kneading of various materials which comprises two cylindrically shaped troughs connected together longitudinally, two similar kneading blades in reversed end-for-end relation, each mounted for rotation in a trough and in intermeshing relation, means for rotating the blades in synchronism and in opposite directions, each blade comprising two end units and a plurality of intermediate units at least two of which are in reversed end-for-end relation, each unit comprising at least two helically disposed leading edges and a cut-out portion at one end of one edge and another cut-out portion at the opposite end of the other edge, the adjacent cut-out portions of adjoining units forming escape openings, at a given instance during rotation each escape opening of one blade lies in a plane passing through the center of rotation of the blade which is at right angles to another plane passing through the center of rotation and the crests of the leading edges of the other blade thus providing a means for the escape of material from which it is positioned to be engaged by the leading edge of the other blade.

6. Apparatus according to claim 5 which comprises leading edges more than one-half the length of each unit arranged to overlap the leading edges of the other blade.

7. Kneading apparatus which comprises two cylindrically shaped troughs joined together longitudinally with a saddle therebetween, a kneading blade mounted on shaft means in each trough, said blades being identical and in reversed end-for-end intermeshing relation, means for rotating the shafts in opposite directions, each blade having a plurality of connected units with at least two helically disposed diametrically opposite leading edges, the adjacent units being in reversed end-for-end relation with the edges of adjacent units converging and diverging, the opposing pairs of units in reversed end-for-end relation on the two shafts defining an intermediate kneading zone and said apparatus comprising a plurality of kneading zones including an inlet zone, an outlet zone and at least one intermediate zone, said leading edges being more than half the length of each unit and being disposed to overlap the leading edges of the corresponding unit of the other blade, the edges at the ends of the units being cut out and forming with a corresponding cut-out portion of the adjacent unit an escape opening, at a given instance during rotation each escape opening of one blade lies in a plane passing through the center of rotation of the blade which is at right angles to another plane passing through the center of rotation and the crests of the leading edges of the other blade whereby material forced through the openings is positioned to be engaged by the diverging edges of the other blade, the profiles of the leading surfaces of the units being involute curves and following the helical direction of the edges, said blades being in such close proximity to each other and the troughs that the material being kneaded is forced between the involute profiles and between the profiles and the troughs, and means for adding material to and removing material from the apparatus.

8. A kneading apparatus according to claim 7 in which the blades are formed of a plurality of separate units mounted on the shafts.

9. A kneading apparatus comprising two cylindrically shaped troughs in close spaced position,

a pair of similar intermeshing kneading blades mounted for rotation in reversed end-for-end relation on substantially parallel axes in the troughs, each blade comprising a plurality of blade units each having two substantially diametrically opposite helical edges which generate a cylinder on rotation, one end of the unit being cut away beyond one end of one helical edge and the other end of the unit being cut away beyond the opposite end of the other helical edge, adjacent units being arranged in the blade in reversed end-for-end relation with the cut-out portions next to each other forming escape openings, the opposing pairs of units in reversed end-for-end relation on the two shafts defining an intermediate kneading zone and said apparatus comprising a plurality of kneading zones including an inlet zone, an outlet zone and at least one intermediate zone, at a given instance during rotation each escape opening of one blade lies in a plane passing through the center of rotation of the blade which is at right angles to another plane passing through the center of rotation and the crests of the leading edges of the other blade, the leading edges being more than one-half the length of the units so that their end portions at the escape openings overlap, each unit having two involute profile surfaces extending from the hub portions to the leading edges and so helically disposed that they follow the leading edges, the profile surfaces being forward of the leading edges as they rotate, the two blades being so mounted with respect to each other and the troughs that the profile surfaces and the leading edges are in such close relation to each other and the troughs as to exert a smearing action of the material between them.

10. In the apparatus of claim 9, said units having leading edges with such a helical pitch that the forward end in the direction of rotation leads the rearward end from 45° to 90°.

11. In the apparatus of claim 9, the leading edges of two adjacent units at the escape opening being in converging relation while the adjoining leading edges of the other blade are in diverging relation.

12. Kneading apparatus which comprises two cylindrically shaped troughs joined together longitudinally with a saddle therebetween, a kneading blade mounted on shaft means in each trough, said blades being identical and in reversed end-for-end intermeshing relation, means for rotating the shafts in opposite direction, each blade having a plurality of connected units with at least two helically disposed diametrically opposite leading edges, the adjacent units being in reversed end-for-end relation with the edges of adjacent units converging and diverging, the opposing pairs of units in reversed end-for-end relation on the two shafts defining an intermediate kneading zone and said apparatus comprising a plurality of kneading zones including an inlet zone, an outlet zone and at least one intermediate zone, each pair of units having an open portion which, at a given instance during rotation, lies in a plane passing through the center of rotation of the blade which is at right angles to another plane passing through the center of rotation and the crests of the diverging edges of the other blade of that zone whereby material forced through the open portion is positioned to be engaged by the diverging edges, each pair of opposite units providing a kneading stage in which the material being kneaded moves in opposite directions and remains unless displaced by added

material, and means for adding material at the inlet zone and removing the material at the outlet zone.

RAYMOND H. JEBENS.
